UNITED STATES PATENT OFFICE.

GEORGE A. LEWIS, OF NAUGATUCK, CONNECTICUT.

DESIGN FOR AN OVERSHOE.

SPECIFICATION forming part of Design No. 14,341, dated October 2, 1883.

Application filed August 20, 1883. Term of patent 7 years.

To all whom it may concern:

Be it known that I, GEORGE A. LEWIS, of Naugatuck, in the county of New Haven and State of Connecticut, have invented a new Design for Overshoes; and I do hereby declare the following, when taken in connection with accompanying drawing and the letters of reference marked thereon, to be a full, clear, and exact description of the same, and which said drawing constitutes part of this specification, and represents a perspective view.

This invention relates to a design for the ornamentation of the front portion of an overshoe; and it consists in the representation of a series of ribs running from the sole at each side upward and backward, those on one side meeting those from the opposite side on the central line at the top, as shown in the accompanying illustration and hereinafter described.

The cut of the shoe is immaterial to this design. Over the front portion of the shoe se-

ries of ribs *a* *b* are represented, those *a* extending from one side upward and backward to the center line down the instep, and those *b* in like manner extending from the sole on the opposite side upward and backward, meeting the series *a* on the said central instep-line, and as shown in the accompanying illustration. 25

I claim—

The herein-described design for overshoe, 30 consisting of the representation of a series of ribs, *a*, extending from the sole at one side upward and backward to the central instep-line, and a second series, *b*, extending from the sole on the opposite side upward and backward to 35 meet the series *a* on said central instep-line, as described, and shown in the accompanying illustration.

GEO. A. LEWIS.
